CLOCK SYNCHRONIZER

Henry Maerz, Brooklyn, N. Y., assignor to Self Winding Clock Company, Inc., a corporation of Delaware

Application June 3, 1947, Serial No. 752,110

1 Claim. (Cl. 58—37)

1

This invention relates to clock synchronizers and more particularly to single stroke synchronizers which reset the clock hands by direct rotation thereof, and is especially adaptable for use in a subsidiary clock system.

Synchronizers of the above type periodically reset the clocks to a predetermined position by forcibly rotating a hand thereof with a single stroke of a synchronizing lever actuated by an electromagnet in the subsidiary clock which in turn is energized by the closing of a circuit in a master clock, such single stroke synchronizing action accomplishing the resetting in a single quick motion.

A friction coupling or clutch interposed between the clock hand and the sensitive balance wheel and other escapement mechanism may offer sufficient resistance to transmit severe torque through the gear train to such sensitive parts with possible injury thereto, as the result of such sudden stroke. While loosening such friction coupling or clutch would help to protect the delicate escapement mechanism, it would allow the hand to slip especially if it is large and heavy, thereby resulting in an unreliable time indication during the hour.

In addition, if the synchronizing electromagnet in the subsidiary clock should remain energized, due to some defect in the circuit thereof, or if a defect in the master clock should cause the synchronizing electromagnets in all the subsidiary clocks to remain energized, the braking effect of the synchronizing lever on the clock hand transmitted through the friction coupling to the escapement mechanism would cause the clock or clocks to stop. Since common clock escapements, as for instance those of pendulum clocks and balance wheel clocks, do not automatically resume operation when the oscillating members are at rest, special and costly self-starting devices are required or manual restarting becomes necessary. This is a very serious problem in subsidiary clock systems having a large number of clocks, some of which may be relatively inaccessible, for it requires a great deal of time and considerable cost and inconvenience to restart each clock.

It is among the objects of this invention to provide a clock synchronizing device that is reliably actuated by a single impulse from a remote source and requires but few moving parts, that is easy to assemble, neat, compact and sturdy in construction and not likely to get out of order, that will provide positive and effective coupling between the clock hand and the gear train driving the same, that affords positive and reliably quick automatic resetting of a clock hand to correct position without reorganization of the construction of the clock and without danger, either of injury to the delicate control mecha-

2

nism thereof or of stalling the clock, should the operating instrumentality either of an individual clock or of a master clock controlling a whole battery of clocks be frozen or jammed.

According to the invention, a driving member is rigidly connected to the arbor driving the clock hand being synchronized, the latter being affixed to a shaft idly mounted on one end of said arbor. A driven member affixed to said shaft is normally operatively connected to said driving member by resilient means, thereby rotating said shaft and the clock hand thereon. Periodically a synchronizing impulse energizes an electromagnet in the clock to pivot a synchronizing lever which sets the clock hand to a predetermined position and at the same time disconnects the driven member from the driving member. When the synchronizing period is over, the lever will pivot back to its original position and the driven member will again be operatively connected to the driving member to continue the rotation of the clock hand.

In the accompanying drawings in which are shown one or more of various possible embodiments of the several features of the invention,

Fig. 1 is a front elevational view of a clock illustrating one embodiment of the synchronizing mechanism,

Fig. 2 is a fragmentary view on a larger scale showing the synchronizing mechanism,

Fig. 3 is a sectional view taken along line 3—3 of Fig. 2,

Fig. 4 is a perspective view of a portion of the synchronizing mechanism showing the sleeve on which is affixed the clock hand, the synchronizing stop cam and the driven member,

Fig. 5 is a fragmentary front elevational view illustrating a second embodiment of the synchronizing mechanism,

Fig. 6 is a fragmentary sectional view taken along line 6—6 of Fig. 5,

Figs. 7 and 8 are perspective views of a portion of the second embodiment of the synchronizing mechanism, and

Figs. 9, 10 and 11 are diagrammatic views of a portion of the synchronizer mechanism in various stages of movement of the clock hand.

Referring now to the drawings, in Figs. 1 to 4 is shown a preferred embodiment of the synchronizing device especially suitable for clocks in which the second hand is not mounted on the same arbor as are the minute and hour hands.

The second hand arbor 11 is journaled in bearing openings in the front and rear panels of the clock and is driven by a gear train which is in itself conventional and will not be described inasmuch as it forms no part of this invention.

Arbor 11 has a reduced portion 12 which extends outward from bearing opening 13 in front panel 14, the reduced portion being threaded at

its end as at 15. A disk-shaped driving member 16 having a hub 17 is affixed on reduced portion 12 by means of a set screw 18 threaded in said hub, the latter abutting the shoulder 19 formed at the root of said reduced portion 12.

Rotatably mounted on reduced portion 12 is a shaft 21 in the form of a sleeve, the bore 22 of which is reduced near one end to form a shoulder 23. Sleeve 21 is retained by means of a nut 24, which is threaded on the end 15 of reduced portion 12 and which abuts against shoulder 23 of sleeve 21. Affixed on sleeve 21 at the outer end 22' thereof is a second hand 25, while a substantially annular driven member 26 of resilient spring material is affixed by means of an arm 27 unitary therewith and extending radially inward therefrom to the inner end 21' of sleeve 21. A tooth or projection 28 on one face of member 26 is urged by the resiliency of said member against one of the radiating grooves 20 forming a ring 20' near the periphery of disk 16. A reversely turned flap 29, the front wall 29' of which is bent outward, is formed unitary with annular member 26 for the purpose hereinafter set forth. A synchronizing stop cam 31 having a sleeve 31' rigid therewith, affixed to sleeve 21 as by force fit, enables sleeve 21 and clock hand 25 to be rotated to a predetermined position. Cam 31 is eccentrically mounted on the sleeve 21 and has a straight edge 32 thereon which enables the hand of the clock to be accurately set as will hereinafter be described.

Pivottally mounted on a stud 35 that extends laterally from the frame 14 of the clock is a substantially L-shaped synchronizing lever 36, the right angled extension 36' of which has a roller 44 thereon rotatably mounted as at 45 and a camming hook 46 affixed to the free end thereof by screws 47, the end of said hook being beveled as at 48. Also pivottally mounted on said stud 35 and affixed to said synchronizing lever 36 is a lever 37. An electromagnet 39 is supported from the frame by a bracket 40 and has an armature 41 pivoted at one end to the frame as at 42 and having its free end pivottally connected to one end of a pitman 43, the other end of the pitman 43 being pivottally connected to an arm 38 extending from lever 37.

In normal operation, sleeve 21 carrying second hand 25 is driven by second hand arbor 11 by means of the driving member 16 on the latter and driven member 26 with tooth 28 thereon, the resiliency of annular driven member 26 being sufficient to urge the projection or tooth 28 into frictional engagement with ring 20' on disk 16 and thus insure positive drive of sleeve 21.

At predetermined intervals a synchronization impulse is delivered to electromagnet 39 from some remote source (not shown). Energization of electromagnet 39 will cause its armature 41 to quickly pivot upward about its pivot 42, thereby raising pitman 43 and pivoting synchronizing lever 36 downward to drive roller 44 against stop cam 31 causing the latter to rotate sleeve 21 until the front edge of arm 36' is flush with the straight edge 32 of stop cam 31. This will occur when the second hand 25 affixed to the outer end 22' of sleeve 21 is indicating the 60 minute position. As sleeve 21 is rotated, the projection or tooth 28 will ratchet over grooves 20 of ring 20' and transmit but little shock to the escapement mechanism. As synchronizing lever 36 approaches the limit of its stroke, the beveled edge 48 of camming hook 46 will contact the outwardly bent front wall 29' of flap 29 and as the

lever 36 continues its movement and hook 46 is urged further into flap 29, the resilient annular member 26 will be urged away from disk 16, withdrawing tooth 28 from ring 20', thus permitting the second hand arbor 11 to turn freely as the gear train is no longer affected by the braking action of the synchronizing lever. As there is no longer any coupling between sleeve 21 and the gear train, there is no danger of the latter being stopped in the event that electromagnet 39 should remain energized.

A second embodiment of this invention shown in Figs. 5 to 11 of the drawings is especially suitable for clocks in which the second, minute and hour hands are mounted coaxially with each other and is illustratively shown as applied to a pendulum type clock.

The second hand arbor 50 has a reduced portion 51 extending laterally from the frame 52 of the clock. A driving member or ratchet wheel 53 having a plurality of symmetrical teeth 54 on the periphery thereof is affixed to reduced portion 51 by a set screw 55 in the hub 56 thereof, the end of reduced portion 51 extending slightly beyond the face of the ratchet wheel as at 57. A shaft 58 which mounts the second hand 77 at one end has a bearing opening 59 at its other end encompassing the extending end 57 of arbor 50 on which it is idly mounted. Affixed to said shaft 58 is a plate or disk 60 having a ratchet pawl 61 pivotally mounted on a stud 62 on one face thereof. Ratchet pawl 61 is urged against the teeth 54 of ratchet wheel 53 by a leaf spring 63 bent over the disk as at 64 and affixed thereto by a stud 65 extending laterally from said disk on the opposite side to which ratchet 61 is pivotally mounted. Shaft 58 is journalled in and has a reduced end 66 which extends from a sleeve 67 unitary with a support plate 68 affixed to the frame of the clock as at 52'.

The bore 69 of sleeve 67 is reduced at one end to form a shoulder 70 against which the shoulder 71 formed at the root end of the reduced portion 66 of shaft 58 abuts. This prevents axial movement of shaft 58 which might cause ratchet pawl 61 to slip off the teeth 54 of ratchet wheel 53.

Idly mounted on sleeve 67 is a gear 72 having a sleeve 73 unitary therewith and coaxial with and encompassing sleeve 67. A gear 74 is idly mounted on sleeve 73 and has a sleeve 75 unitary therewith which is coaxial with and encompasses sleeves 67 and 73. Gears 72 and 74 which drive the minute and hour hands respectively are in turn driven by a conventional gear train which will not be described inasmuch as it forms no part of this invention.

Coacting with the said stud 65 and ratchet pawl 61 is the synchronizing lever 78 pivotally mounted on a stud 79 extending laterally from the frame 52 of the clock. Also pivotally mounted on said stud 79 and affixed to said synchronizing lever 78 is a lever 80 having a yoke 81 extending therefrom. Lever 80 is affixed to lever 78 by a screw 82 which extends through an arcuate slot 83 in lever 80 to permit adjustment of the latter with respect to lever 78.

An electromagnet 84 is supported from the frame by a bracket 85 and has an armature 86 pivoted at one end as at 87. The armature has a stud 88 extending from the free end thereof which is straddled by the arms 89 of yoke 81 whereby movement of the armature 86 will be transmitted to lever 78. A yoke 90 at the free end of lever 78 coacts with stud 65 when the lever is pivoted, as will be hereinafter described. Extending from

the closed portion 31 of the yoke is a ratchet pawl release arm 32 which is curved at its free end and has a shoe 33 unitary therewith which will contact the free end 61' of ratchet pawl 61 when the lever 78 has been pivoted to pivot the ratchet pawl about its stud 62 and to disengage it from the ratchet wheel.

In normal operation shaft 58 carrying second hand 77 is driven by second hand arbor 59 by means of ratchet wheel 53 on the latter, the tension of spring 63 being sufficient to urge ratchet pawl 61 into engagement with the teeth 54 of ratchet wheel 53 and insure positive drive of said shaft 58.

At predetermined intervals a synchronizing impulse is delivered to electromagnet 84 from some remote source (not shown). Energization of electromagnet 84 will cause its armature 86 to be quickly pivoted upwards, thereby pivoting synchronizing lever 78 downward and driving the yoke end 90 of lever 78 against stud 65 which has been revolving around shaft 58 as the latter rotates.

If for any reason the clock should be, for example, 15 seconds slow when the synchronizing impulse is received, the yoke end 90 of lever 78 would be forced against stud 65 which at this time would be in the position shown in Fig. 10. As disk 60 is only coupled to ratchet wheel 53 by the tension exerted on ratchet pawl 61 by spring 63, the force of the synchronizing blow of yoke 90 against stud 65 will rotate disk 60 in a clockwise direction and the ratchet pawl 61 will ride over the teeth of ratchet wheel 53 until the yoke end 90 of the lever 78 straddles stud 65 which would be in the position shown in Fig. 11. In this position the second hand of the clock will indicate the 60 minute position. If the clock should be say 15 seconds fast when the synchronization impulse was received, lever 78 and stud 65 would be in the position shown in Fig. 9 and disk 60 would be rotated in a counterclockwise direction to the position shown in Fig. 11 to properly set the second hand. If the clock is on time when the synchronizing impulse is received, since stud 65 and lever 78 would be in the position shown in Fig. 11, no movement could be imparted to disk 60 and shaft 58 by lever 78 inasmuch as the stud 65 would already be in the proper position for such time indication. It is to be noted that the symmetrical teeth 54 on ratchet wheel 53 permit ratchet pawl 61 to ride thereover in both a clockwise and counterclockwise, thus permitting synchronization when the clock is fast or slow.

As yoke 90 is driven against stud 65, shoe 33 will be urged against the free end 61' of ratchet pawl 61 and will pivot the latter against the tension of spring 63 so that it no longer engages the teeth on ratchet wheel 53. This will occur at each synchronizing impulse and thus permit the second hand arbor 59 to turn freely and as there is no longer any coupling between disk 60 and shaft 58, there is no danger of the escapement mechanism being stopped in the event the impulse to electromagnet 84 is unduly prolonged.

Although the coupling between the driving member and driven member of either of the embodiments herein is disengaged only when the synchronizing lever has reached the end of the stroke, it is to be understood that it would be a relatively simple expedient to modify the construction herein slightly so that the coupling could be disengaged at the beginning of the stroke of the synchronizing lever. It is important, however, that such disengagement occur no later than 75

the end of said stroke for if such was the case, the continued braking effect of the synchronizing lever transmitted to the escapement mechanism of the clock would stop the latter with the attendant difficulties heretofore set forth.

Inasmuch as it takes only a relatively small amount of power to drive the clock hand, the resilient member coupling the driving member and the driven member need exert but a small tension to ensure positive coupling. In the case of the first embodiment herein shown, the synchronizing action drives the hand in a clockwise direction and therefore does not have any braking effect on the escapement mechanism until the end of the stroke, at which time however the coupling is disengaged. In the case of the second embodiment, although the hand would be moved in a counterclockwise direction if it was fast, it is moved so quickly to its proper position that the braking effect, which only lasts for a very short interval, is not sufficient to stall the pendulum, the inertia of which keeps it oscillating for several seconds even after the clock is stopped.

It can thus be seen that the use of the device herein will insure positive drive of the clock hand, yet permit resetting of the latter at predetermined intervals without danger of injury to or stoppage of the escapement mechanism of the clock, thereby eliminating the resulting inconvenience that such stoppage or breakage would cause.

As many changes could be made in the above construction, and many apparently widely different embodiments of this invention could be made without departing from the scope of the claim, it is intended that all matter contained in the above description or shown in the accompanying drawings shall be interpreted as illustrative and not in a limiting sense.

Having thus described my invention what I claim as new and desire to secure by Letters Patent of the United States is:

In a clock of the type comprising a frame, a gear train supported by said frame, an arbor journaled in said frame and driven by said gear train and a clock hand; the combination therewith of a disk affixed to said arbor and having a plurality of radially extending grooves forming a ring on one face thereof, a shaft rotatably mounted on said arbor and carrying said clock hand, a cam and a resilient ring member coaxial with said shaft, said resilient ring member having a tooth on one face thereof normally urged into engagement with the ring on said disk, a lever pivoted on said frame, a roller on said lever, means to pivot said lever and urge said roller against said cam to rotate the latter and said clock hand operatively connected thereto, a flap on said resilient ring member in juxtaposition to said tooth, a camming hook affixed to said lever, said camming hook engaging said flap and camming said resilient ring member outward, thereby disengaging said tooth from said ring when said lever has been pivoted to the limit of its stroke.

HENRY MAERZ.
